UNITED STATES PATENT OFFICE

146,405

DESIGN FOR A COVERED RECEPTACLE

William C. Bundy, West Los Angeles, Calif.

Application January 26, 1946, Serial No. 125,999

Term of patent 3½ years

(Cl. D44—15)

To all whom it may concern:

Be it known that I, William C. Bundy, a citizen of the United States, residing in the city of West Los Angeles, county of Los Angeles, and State of California, have invented a new, original, and ornamental Design for a Covered Receptacle, of which the following is a specification, reference being had to the accompanying drawing, forming a part thereof.

Fig. 1 is a perspective view of the covered receptacle showing my new design, and Fig. 2 is another perspective view of the receptacle, taken at an angle to show details that do not appear in Fig. 1.

I claim:

The ornamental design for a covered receptacle, as shown and described.

WILLIAM C. BUNDY.
